VOICE RECORDING SYSTEMS WITH
PLURAL INPUT STATIONSStuart David Le Barre, 14021 Lincoln,
Oak Park, Mich. 48237Continuation of application Ser. No. 828,645, July 21,
1959. This application Feb. 23, 1965, Ser. No. 440,342
1 Claim. (Cl. 340—172.5)

This invention relates to a system for the recording of intelligence received from a plurality of sources and for programming the recordation and is a continuation of my copending application Ser. No. 828,645, filed July 21, 1959.

In order to maintain close cost and production control over, for example, operation of a plurality of machine tools, it is often desired to provide a record of the time expended on each machine tool operation by the individual machine tool operators. Preferably, for purposes of efficiency, this time keeping function is centralized.

The system of the present invention provides for the relatively efficient transmission of data from a plurality of outlying stations located, for example, adjacent each machine tool for which such records are to be kept, for recording at a central console. The recording medium becomes the means of storing the intelligence transmitted. The system automatically provides for the positive control of any number of such stations by a lesser number of relay banks, each of which accommodates, in the exemplary system described hereinafter, five stations. Each relay bank has a recording device associated therewith. The relay banks function to both control the input of intelligence from the machine tool stations associated therewith so that only one station is capable of transmitting intelligence at one time and also provide for a plurality of auxiliary circuits so as to facilitate oral communication, visual and audio signaling, positive visual and audio indication of recorder failure, and automatic switching of intelligence between a defective recorder and a stand-by recorder.

Accordingly, one object of the present invention is to provide a system for controlling the centralized recordation of intelligence from a plurality of dispersed sources.

Another object is to provide a system for the recording of intelligence having primary and secondary recording devices and means for automatically switching therebetween.

Another object is to provide a system for controlling the recording of intelligence from a plurality of sources comprising primary and secondary recording devices, transfer means for switching intelligence from the secondary to the primary recording device upon the initiation of operation of the primary device, means connected to the transfer means and to the intelligence sources for automatically relaying intelligence from one of the sources to the transfer means and means for locking out the remaining sources while the one source is in operation.

Other objects and advantages of the present invention will become apparent from the following description wherein reference is made to the drawings in which:

FIGURE 1 shows, in diagrammatic form, a recording device, a transfer switch, a power supply, and a chime drive circuit;

FIG. 2 shows, in diagrammatic form, a pair of relay banks and a chime control circuit; and

FIG. 3 shows, in diagrammatic form, a call station, a relay bank and accessory circuits related thereto.

Referring to FIGS. 1, 2 and 3 of the drawings which are to be arranged in side by side sequential relation, an exemplary embodiment of a program system in accordance with the present invention comprises a plurality of call stations SA1 through SA5, SB1 through SB5, and SC1 through SC5, one of which (SA1) is shown in detail. The

2

components and operation of the call station SA1 will be described in detail, it being understood that the remaining call stations are similarly constituted and function in a like manner. The call stations are connected in circuit with an appropriate number of relay gangs RA, RB and RC. In the embodiment illustrated, five call stations are connected to each relay gang, for example, the A, B and C series of call stations are connected to relay gangs RA, RB, and RC, respectively. Each of the relay gangs RA, RB, and RC is connected through a transfer switch TS-A, TS-B, and TS-C, respectively, to a recording device, for example a tape recorder, TR-A, TR-B, and TR-C, respectively. A transfer switch TS-S and tape recorder TR-S are provided in operative association on a stand-by status with the relay stations RA, RB, and RC so as to be connected thereto at such time as the primary recorder associated therewith fails, as will be described.

A power supply is provided for the program system comprising preferably a 110 v. A.C. source, a 24 v. A.C. source, and a 24 v. D.C. source.

The components of the program system other than the fifteen call stations SA1 through SA5, SB1 through SB5, and SC1 through SC5, which are located, for example, at outlying positions within a manufacturing facility, are located at a central control point. As will be apparent from the following description, all connections between the outlying stations and the components of the program system at the control console are low voltage connections, thus facilitating the installation and maintenance of the system and reducing the cost thereof.

The transmission of information from an outlying station SA1 to the control console for recording is initiated by lifting, for example, a conventional telephone receiver off its hook, thereby closing a switch hook 10. Closure of the contact 10 closes a circuit from the positive side of the 24 v. D.C. source through a conductor 100, relay RA1, conductor 101, switch hook contact 10, the normally closed contact 11 of a switch 12 to ground, thereby energizing the relay RA1. Upon energization, the relay RA1 closes a contact 15 thereby completing a circuit from the 24 v. D.C. source, through the conductor 100, contact 15, conductor 102, to a terminal 16 and normally closed contact 18 of a transfer switch TS-A thereby completing a circuit through a transfer switch relay TSRA-1 to ground. The above circuit also energizes a pair of stand-by transfer switch relays TSR-S1 and TSR-S2. The effect of the energization of the relays TSR-A1, TSR-S1 and TSR-S2 will be discussed hereinafter. Relay RA1, upon energization, also closes a contact 20 completing a lock-out circuit from one side of the 110 v. A.C. source, through a conductor 104, contact 20, contacts 21, 22, 23, and 24 of relays R-A7, R-A8, R-A9 and R-A10, respectively, through relay RA6 and conductor 105 to the other side of the 110 v. A.C. source. Energization of the relay RA6 opens contacts 25, 26, 27 and 28 thereby locking out relays RA2, RA3, RA4, and RA5. The effect of the lock-out circuit on the program system 10 is to prevent more than one station from transmitting intelligence to the recording device at one time. It will be seen from inspection of the wiring diagram that energization of any one of the relays R-A1, R-A2, R-A3, R-A4, and R-A5 and the lock-out relay R-A6, R-A7, R-A8, R-A9, or R-A10 associated therewith, respectively, locks out the non-energized relays, preventing their subsequent energization until the relay initially energized is de-energized.

Energization of the relay RA1 also closes contact 20 to complete a circuit from 110 v. A.C. source through conductor 104, contact 20, contacts 21, 22, 23, and 24, and relay RA11 to conductor 105 to the other side of the 110 v. A.C. source. Energization of the relay RA11 closes contact 30 completing an indicator light circuit from the positive side of the 24 v. D.C. source through con-

ductor 100, through conductor 106 into the transfer switch TSA, to contact 31 therein, and, upon energization of the transfer switch relay TSRA1 through contact 31, terminal 32, conductor 108, contact 30, conductor 109, and green indicator light (G) to ground. Energization of the relay RA11 also completes a similar 24 v. D.C. circuit to the contact 30 then upwardly through a panel indicating light (PL) through conductor 103 to ground. The panel light (PL) gives visual indication at the control console that a particular station is transmitting intelligence through the recording system and the green light (G) at the station indicates that the system is capable of accepting the intelligence transmitted.

Energization of the relay RA11 also closes contact 40, completing a circuit from the positive side of the 24 v. D.C. source through conductor 100, contact 40, relay RA16, and conductor 103 to ground. Energization of relay R-A16 closes contact 50, completing a circuit from the positive side of the 24 v. D.C. source through conductor 100, contact 50, conductor 110, to red light (R) then to ground. Thus, red indicator light (R) is energized immediately upon closing the switch hook contact 10, the green indicator light being energized only after a recording device TR-A commences operation, as will be described.

Energization of relay RA16 also closes contact 60, completing a circuit from the positive side of the 24 v. D.C. source through conductor 100, contact 60, conductor 111, relay TSR-A2 to ground. Energization of the relay TSR-A2 starts the recorder TR-A in operation, as will be discussed.

Energization of relay RA16 also closes contacts 70 and 71 thereby completing a microphone circuit from terminals 72 and 74 of a recorder jack RJ-A, through a pair of switches 75 and 76, through conductors 115 and 116, contacts 70 and 71, conductors 118 and 119, switches 78 and 69, conductors 120 and 121, to a microphone (MIC).

When an attendant at the control console wishes to attract the attention of, for example, a machine tool operator at an outlying station S-A1, the attendant rotates a movable finger 82 on a multi-position switch 83 having a plurality of contacts 84 thereon until the finger 82 makes contact with the contact 84 of a desired circuit. The attendant then pushes a button 85, closing a circuit through the secondary of a transformer 86, push-button 85, finger 82, contacts 84, conductor 127, through a signal 87, through a conductor 128, to the other side of the secondary of the transformer 86.

When a party at the outlying station S-A1 desires to attract the attention of an attendant at the control console, to initiate an oral conversation, the party reverses the switch 12, closing a chime circuit from the 24 v. D.C. source through conductor 100, conductor 129, chime relay CRA1, conductor 130, and contact 88 of switch 12 to ground.

Energization of relay CRA1 closes contact 89, completing a chime circuit from the 24 v. D.C. source through conductor 100, conductor 129, contact 89, conductor 131, normally closed push-button 90, conductor 132, and conductor 103 to ground. The attendant can open the chime circuit by opening the push-button 90.

Energization of relay CRA1 also closes contact 91, completing a circuit from one side of the 110 v. A.C. source through conductor 103, conductor 133, contact 91, conductor 134, through chime motor coil 92, conductor 135, conductor 104 to the other side of the 110 v. A.C. source. Thus, it will be seen that closure of contact 91 completes a circuit through the chime motor circuit 92 thereby energizing motor 92 to drive a pair of cams 93 and 94 having lobes angularly displaced from one another so as to open a pair of switches 95 and 96 in a predetermined sequence. Cam 93 opens and closes the switch 95, completing a circuit through the secondary of a chime transformer 97, chime coil 98 to ring a chime 99. The

cam 94 is so related to the cam 93 that it closes the switch 96 prior to closure of the switch 95, thereby to place the chime motor across the conductors 133 and 135 of the 110 v. A.C. The switch 96 remains closed until after the switch 95 opens, thereby insuring that the circuit through the secondary of the transformer 97 and chime coil 98 is broken before the chime motor 92 is de-energized to insure that the chime coil 98 is not left in the energized condition.

An oral inter-communication system (IC) is provided so that an attendant at the control console may converse with a party at the outlying station S-A1. The attendant first signals the party with the buzzer in a manner discussed hereinbefore. The attendant then throws the switches 78 and 79 to the IC position, thus taking the microphone MIC out of the recorder circuit and putting it into the inter-communication circuit. Movement of the switches 78 and 79 closes a pair of switches 80 and 81, thereby completing a microphone circuit from the station S-A1 through conductors 120 and 121 and a receiving circuit through conductors 125 and 126. When the attendant at the control console completes his conversation with the party at the station S-A1, the switches 78 and 79, 80 and 81 are reversed, thus shorting the station receiver circuit and switching the station microphone circuit into the program system.

Energization of the relay CRA1 also closes a contact 200 completing a circuit from the 6 v. A.C. secondary of a transformer 201 through a conductor 136, contact 200, indicator light 202, conductor 137 to the other side of the secondary of the transformer 201. Energization of the light 202 gives a visual indication that a party at the station S-A1 is desirous of orally communicating with the attendant at the control console.

The outlying station SA1 is provided with a lock, preferably of the 24-hour type, that is permanently connected in circuit with the 24 v. A.C. secondary of a transformer 205, conductors 138 and 139, and a step-up transformer 206. The step-down transformer 205 and step-up transformer 206 are provided for the clock circuit so as to require only a 24-volt wire between the station SA1 and the control console.

Operation of the recorder TR-A is initiated by the transfer switch relay TSR-A2 upon closing of the contact 60 of the relay RA-16. The transfer switch relay TSR-A2 opens a normally closed contact 210, thereby opening a normally closed circuit through a starting solenoid 211 and a recorder relay TR-R1, a power supply 212 and the contact 210. The normally energized relay TR-R1, upon de-energization, allows a contact 214 to close, thereby completing a circuit from the one side of the 110 v. A.C. source through the contact 214, through a motor winding 215 and recorder relay TR-R2 to the other side of the 110 v. A.C. source. Upon energization, the relay TR-R2 closes a normally open contact 216, completing a circuit from the 24 v. D.C. source through the contact 216 to the transfer switch relay TSR-A1. Energization of the transfer switch relay TSR-A1 opens the contact 18, thus de-energizing the stand-by transfer switch relays TSR-S1 and TSR-S2. Thus it will be seen that the stand-by recorder TR-S is energized until such time as the primary tape recorder TR-A is energized and in operation.

The transfer switch relay TSR-A1 also closes a pair of contacts 220 and 221, thereby completing a microphone circuit from the terminals 72 and 74 of the transfer switch TS-A to the recorder TR-A, and opening the microphone circuit leading to the stand-by recorder TR-S.

If for some reason the recorder TR-A draws too much current, a fuse 225 blows, thereby energizing a normally short-circuited relay TR-R3 which closes a contact 226, completing an alarm circuit from a 6 v. A.C. source through an alarm 227 through the contact 226 to the other side of the 6 v. A.C. source. A visual signal is

given upon blowing of the fuse 225 by a pilot light 228 on the recorder TR-A.

An example of the operation of the program system, the sequence of events upon energization of the system from an outlying call station will be traced. Assuming that the party at the outlying station desires to record information, he picks up a receiver, for example, a conventional telephone receiver, thereby closing the switch hook contact 10 and energizing the relay R-A1. Energization of the relay R-A1 closes contact 15 and energizes transfer switch relays TSR-S1 and TSR-S2, thereby initiating operation of the standby recorder TR-S in a manner similar to the energization of the recorder TR-A discussed hereinbefore. Energization of the relay R-A1 also closes contact 20, thereby locking out the call stations S-A2, S-A3, S-A4, and S-A5. Closure of the contact 20 also energizes relay R-A11, thereby closing contact 30 and, upon energization of the transfer switch delay TSR-A1, the green indicator light circuit. Energization of the relay R-A11 also closes contact 40, thereby energizing relay R-A16. Energization of relay R-A16 closes contact 50 thereby energizing the red indicator lights on each of the stations S-A1 through S-A5. The relay R-A16 also closes a contact 60, thereby energizing the transfer switch relay TSR-A2 to close the contact 210 and initiating operation of the recorder TR-A as discussed hereinbefore. The relay R-A16 also closes the contacts 70 and 71, completing a microphone circuit from the station S-A1 to the recorder TR-A through the contacts 220 and 221 which were closed upon energization of the transfer switch relay TSR-A1, thereby placing the system in condition for the recording of intelligence from the station S-A1.

While it will be apparent that the embodiments of the invention herein disclosed are well calculated to fulfill the objects of the invention, it will be appreciated that the invention is susceptible to modification, variation and change without departing from the proper scope or fair meaning of the subjoined claim.

I claim:

1. A system for recording verbal conversation at a central station from a plurality of remote sources comprising:
a plurality of primary recording devices,
a secondary recording device,
means at each of said remote sources for energizing and conditioning said primary and secondary recording devices for the reception of intelligence, means for routing said verbal conversation to said secondary recording device,
transfer means for sensing the condition of said primary recording devices prior to recording of said verbal information on said secondary recording device, means for switching from the secondary recording device to one of said primary recording devices upon the availability and commencement of operation of any one of said primary recording devices,
means for locking out the remaining remote sources while one of said remote sources is in operation, indicator means at said central station and at each of said remote sources for indicating the condition of the recording system,
an oral communication connection extending between each of said remote sources and said central station, and
indicator means at each of said remote sources and said central station for indicating the condition of said oral communication system.
